REFRIGERATION SYSTEM

George E. Hulse, New Haven, Conn., assignor to
The Safety Car Heating & Lighting Company,
a corporation of New Jersey

Application September 20, 1930
Serial No. 483,196

15 Claims. (Cl. 62—4)

This invention relates to refrigeration systems.

One of the objects of this invention is to provide a simple refrigeration system which will be practical and efficient in use. Another object of this invention is to provide a refrigeration system of easy manufacture and durable construction. Another object of this invention is to provide a refrigeration system which will be efficient and lasting in operation. Another object of this invention is to provide a refrigeration system having means of regulating its prime mover. Another object is to provide a device of the above nature which will require a minimum amount of attention in operation and may be operated by labor unskilled in the art. Another object in this invention is to provide a refrigeration system which may operate efficiently with the number of actuations of its parts reduced to a minimum. Another object of this invention is to provide a refrigeration system in which the starting means for the prime mover is of rugged character and dependable action. Other objects will be in part obvious and in part pointed out hereinafter.

This invention accordingly consists in the features of construction, combination of elements, and arrangement of parts as will be exemplified in the structure to be hereinafter described, and the scope of the application of which will be indicated in the following claims.

30 The drawing in which is shown one of the various possible embodiments of this invention is a diagrammatic plan.

Similar references and character refer to similar parts throughout the several views of the drawing.

As conducive to a clearer understanding of some of the features of this invention, it may at this point be convenient to note that in refrigeration systems of the above character in which an internal combustion engine as a prime mover is automatically started considerable difficulty has been experienced in providing means for simultaneously choking the same. As is well-known, an engine of this type starts with much greater ease if it is choked and this is especially true in cold weather. Manual means for choking engines of this type have been attempted but this often results in a great deal of inconvenience. This invention aims to provide a practical device in which the above noted difficulties are reduced to a minimum.

Referring now to the drawing in detail, there is shown a refrigeration system consisting of an internal combustion engine 10 driving a compressor 11 by means of a shaft 12. Secured to

the shaft 12 is a speed reducing device 13 and an automatic clutch 14 preferably of the centrifugal type. The apparatus generally indicated by the numeral 15 consists of a refrigeration unit of the usual compression-expansion type with refrigerating coils 16 leading into the chamber 17 whose temperature is to be regulated.

An electric starting motor 18 is connected to the driving shaft of the engine 10 by any convenient means 19 such as pinions or a belt. A source of current 20 which may consist of storage battery, a generator or both, according to the specific conditions under which this system is to be employed, has one terminal connected directly to starting motor through a line 21. The opposite terminal of this source of current 20 is connected to a solenoid 22.

A double contact thermostatic switch 23 is located in the interior of the chamber 17. One of the contacts 26 in the thermostatic switch 23 is grounded; the other contact 24 is connected to the solenoid 22 through the line 24a. A line 25 extending from the thermostatic switch 23 runs to the line 21 and thus to the motor.

It will be seen that when the thermostatic switch 23 is actuated by a change in temperature in the chamber 17 and makes contact with 24, as will occur when the temperature in this chamber is above that preferred, the solenoid 22 will be energized through circuits 21, 25, 23, 24a and 22a. This solenoid 22 forms a part of an automatic switch and upon energization an arm 27 of its core 28 will make contact with points 29 and 29a. As shown in the drawing the automatic switch 30 is closed in its normal position when the motor 10 is at rest making contact with two terminals 31 and 32. It will be seen that by this simple construction, when the thermostatic switch 23 makes contact at 24 in the above described manner automatically closing switch 27, a circuit from the source of current to the motor is established, consisting of the lines 22a, 29, 27, 29a and 28b and 21.

A pressure-responsive member 34 is connected through a conduit 35 to the intake manifold 36 of the engine 10. This pipe 35 makes contact with manifold 36 at a point preferably between the cylinder and the throttle. It should be understood, however, that this conduit may be connected to other parts of the engine where variable pressure is available with many advantageous results. This pressure-responsive member 34 is of such a construction that it will readily respond to small changes of pressure, thus contracting and expanding according to these relative pressures.

- and being fully expanded at atmospheric pressures. At the opposite end of this pressure-responsive member 34 is an arm 37 comprising a switch 30 for line 25 as described above. When the engine 10 is at rest so that normal atmospheric pressure is acting on the pressure-responsive member 34, this switch 30 will be closed but upon a sufficient reduction in pressure, this member 34 will contract, opening the switch 30.
- 10 An air choking element 38 disposed on the intake manifold 36 of the engine 10 is secured to leaverage system 39 diagrammatically shown in the drawing. This leaverage system 39 is also secured at 40 to the pressure-responsive member 34 and the choking element 38 and is so adjusted with respect to the member 34 that when this member is fully expanded by normal atmospheric pressure, the choking element 38 is closed. However, when this pressure-responsive member 34 contracts due to a decrease of pressure the choking element 38 is automatically opened by means of the leaverage system 39. It will be seen that this device is of extremely simple construction and well adapted to withstand the wear and tear of constant operation with a minimum amount of attention. Furthermore this apparatus is admirably suited for use as an automatic choking means on all types of internal combustion engines whether or not their motors are used in refrigeration systems, although the above combination is considered most advantageous.
- Considering now the action of this apparatus, let it be assumed that the temperature in the chamber 17 has risen above that preferred for cooling purposes. Under the above set forth conditions the thermostatic switch 23 will make contact at 24. Thus the solenoid 22 will be energized by the circuits 21, 25, 32, 30, 23, 24 and 24a and 22a. Upon energization of the solenoid 22 the switch 27 will be automatically closed, connecting the contacts 29 and 29a. It is assumed that the engine 10 is at rest and under these conditions as above set forth the switch 30 will be closed.
- 45 It will be seen that upon closing the switch 27 a circuit between the source of current 20 and the starting motor 18 is accomplished. This circuit consists of the line 21 and 22a, 29, 27, 29a and 29b. The motor 18 being actuated, the engine 10 is started. It should be noted at this point that the pressure-responsive member being in its normal position, the choke 38 is automatically closed for normal atmospheric pressure is acting upon it, thus facilitating the starting of the engine. As the engine 10 starts, a partial vacuum is created in the manifold 36 and thus in the pressure-responsive member 34 by means of conduit 35. This decrease in pressure will cause this member 34 to contract and upon the contracting of this member 34, the switch 30 will open, thus breaking the circuit between the solenoid 22 and the source of current 20. Upon the deenergization of this solenoid 22, the switch 27 automatically opens thus breaking the circuit between the source of current 20 and the starting motor 18. It will be noted that simultaneously with the above described action the contraction of the pressure-responsive member 34 also actuates the choking element 38, causing it to open to stop further choking action.
- The starting motor 18 having stopped and the choking action having ceased, the engine 10 will attain its normal speed and the centrifugal clutch 14 will be actuated, thus driving the compressor 11. The compressor 11 and the refrigeration ap-

paratus generally indicated at 15 will cause refrigeration in the chamber 17 by means of the coil 16. In this manner the chamber 17 is cooled to a point below the preferred temperature, and when this temperature is reached, thermostatic switch 23 will be actuated to make contact at 26.

It will be noted that by the provision of a double contact thermostatic switch the refrigeration apparatus will cool the chamber below the preferred temperature before arm 23 is sufficiently actuated to meet point 26 and stop this apparatus. Thus the temperature will stay below or at the preferred temperature for a relatively longer length of time thus reducing the number of times which the apparatus must be started. This reduces the wear and tear of parts greatly and economizes on fuel for the engine and current for the starting motor. The arm of the thermostatic switch 23 is connected to the magneto 41 of the engine 10, this magneto 41 serving as a source of current for the ignition system of the engine. Upon making contact 26 the thermostatic switch automatically grounds the magneto 41, thus stopping the engine 10. The engine being stopped, the parts return to normal condition and the pressure-responsive member 34 expands to close the switch 30.

It will thus be seen that an automatic refrigeration system of simple design and construction has been constructed in which the starting and stopping means of the prime mover in such a system is automatically controlled and adjusted. It should be noted that the controlling means for this system is of such simple construction that little labor will be necessary to insure reliable operation. Refrigeration systems of the above nature are often subjected to rough use and unskilled care. This is especially true when they are used on railroad cars, trucks and other vehicles. Under such conditions these systems are required to work for a considerable length of time under variable conditions with little care, and it is absolutely essential that they be reliable in operation. The simple construction of this system and particularly the pressure-responsive member 34 makes it admirably suited for such conditions. The provision for an automatically adjusted choke for the internal combustion engine of such a system makes for increased efficiency, saves on fuel, and reduces the strain on the source of current by insuring a quick start.

As many possible embodiments may be made of the above invention, and as many changes may be made in the embodiment above set forth, it is to be understood that all matter hereinbefore set forth or shown in the accompanying drawing is to be interpreted as illustrative and not in a limiting sense.

I claim:

1. In refrigeration apparatus, in combination, means adapted to contain a medium whose temperature is to be governed, a refrigerating unit for said means, motive means adapted to actuate an element of said unit, a starting member for said motive means, thermostatic means positioned in the circuit of a source of current and said starting member for controlling the actuation of said member, and means disposed in said circuit adapted to be actuated by variation of pressure from said motive means for regulating the actuation of said member.
2. In refrigeration apparatus, in combination, means adapted to contain a medium whose temperature is to be governed, a refrigeration unit for said means, an internal combustion engine 150

- adapted to actuate an element of said unit, a motor for starting said engine, a circuit of current for said motor, a thermostatic switch enclosed in said containing means and disposed in said circuit for controlling the actuation of said motor, a second switch in said circuit, and a member adapted to actuate said second switch by variation of pressure from said engine for regulating the actuation of said motor. 50
- 10 3. In refrigeration apparatus, in combination, means for containing a medium whose temperature is to be regulated, a refrigeration unit for the regulation of said temperature, an internal combustion engine in said unit, a member actuated by relative pressure from said engine, a starting motor for said engine, a thermostatic switch in said containing means for controlling a circuit to said motor, means for controlling the volume of air intake of said engine actuated by said member, a switch in said starting motor circuit positioned to be actuated by said member, and means connected to the intake pipe of said engine actuated by relative pressure in said pipe for controlling said switch and regulating said air controlling means. 85
- 15 4. In refrigeration apparatus, in combination, enclosing means for a medium whose temperature is to be regulated, a refrigeration unit for said enclosing means, an internal combustion engine for actuating an element of said refrigeration unit, a magneto for supplying ignition current for said engine, and thermostatic means in said enclosing means for grounding said magneto at a pre-determined temperature. 90
- 20 5. In refrigeration apparatus, in combination, means forming a space whose temperature is to be regulated, a refrigeration unit for said space, an internal combustion engine adapted to drive certain parts of said refrigeration unit, an electric motor for starting said engine, a magneto forming a part of said engine, a source of current, a circuit between said source of current and said starting motor, and a thermostatic switch responsive to the temperature of said space in said circuit, said switch being connected with said magneto and having a contact grounded whereby when the temperature of said space is above that preferred said switch closes said circuit and when the temperature of said space is at or below that preferred said switch grounds said magneto. 95
- 25 6. In refrigeration apparatus, in combination, means forming a space whose temperature is to be regulated, a refrigeration unit for said space, an internal combustion engine adapted to drive certain parts of said refrigeration unit, an electric motor for starting said engine, a magneto forming a part of said engine, a source of current, a circuit between said source of current and said starting motor, and switching means in said circuit including a contact, a thermostatic switch arm responsive to the temperature of said space and adapted to engage said contact when the temperature thereof is above that preferred, and a second contact grounded, said switch arm also being connected with said magneto and adapted to engage said last-mentioned contact when the temperature of said space is at or below that preferred. 100
- 30 7. In refrigeration apparatus, in combination, means forming a space whose temperature is to be regulated, a refrigeration unit for said space, an internal combustion engine adapted to drive certain parts of said refrigeration unit, starting means for said engine, means for controlling the air intake of said engine, means responsive to the temperature of said space for controlling the action of said starting means, and means responsive to pressure variation in said engine for regulating the action of said first-mentioned controlling means and modifying the action of said temperature-responsive means. 105
- 35 8. In refrigeration apparatus, in combination, means forming a space whose temperature is to be regulated, a refrigeration unit for said space, an internal combustion engine adapted to drive certain parts of said refrigeration unit, electric starting means for said engine, a source of current, a circuit between said source of current and said starting means, a thermostatic switch responsive to the temperature of said space in said circuit, a second switch in said circuit, said circuit being incomplete until both of said switches are closed, means for controlling the air intake of said engine, and a pressure-responsive apparatus connected to said engine and adapted to control the operation of said last-mentioned means and said second switch. 110
- 40 9. In refrigeration apparatus, in combination, means forming a space whose temperature is to be regulated, a refrigeration unit for said space, an internal combustion engine adapted to drive certain parts of said refrigeration unit, electric starting means for said engine, a source of current, a circuit between said starting means and said source of current, a thermostatic switch in said circuit responsive to the temperature of said space, a second switch in said circuit, said circuit being incomplete until both of said switches are closed, a valve for controlling the intake manifold of said engine, and pressure-responsive apparatus connected to the manifold of said engine and adapted to actuate said valve and said second switch. 115
- 45 10. In refrigeration apparatus, in combination, means forming a space whose temperature is to be regulated, a refrigeration unit for said space, an internal combustion engine adapted to drive certain parts of said refrigeration unit, means for starting and stopping said engine, controlling means responsive to the temperature of said space, and controlling means responsive to pressure variation in said engine, both of said controlling means adapted to coact to control the action of said starting and stopping means. 120
- 50 11. In refrigeration apparatus, in combination, means forming a space whose temperature is to be regulated, a refrigeration unit for said space, an internal combustion engine adapted to drive certain parts of said refrigeration unit, starting means for said engine, controlling means responsive to the temperature of said space, controlling means responsive to pressure variation in said engine, said last-mentioned controlling means adapted to coact with said first-mentioned controlling means to place said starting means in operative condition when the temperature of said space is above that preferred and adapted to stop said starting means when said engine has reached its normal speed of operation. 125
- 55 12. In refrigeration apparatus, in combination, means forming a space whose temperature is to be regulated, a refrigeration unit for said space, an internal combustion engine adapted to drive certain parts of said refrigeration unit, electrical starting means for said engine, a source of current, a circuit between said source of current and said starting means, a thermostatic switch in said circuit and responsive to the temperature of said space, a second switch in 130
- 60 75

- said circuit, said circuit being incomplete until both of said switches are closed, and means for controlling the opening and closing of said second switch in response to pressure variation in said engine.
13. In refrigeration apparatus, in combination, means forming a space whose temperature is to be regulated, a refrigeration unit for said space, an internal combustion engine adapted to drive certain parts of said refrigeration unit, electrical starting means for said engine, a source of current, a circuit between said source of current and said starting means, a thermostatic switch in said circuit and responsive to the temperature of said space, a second switch in said circuit, said circuit being incomplete until both of said switches are closed, and means for controlling the opening and closing of said second switch in response to the operative condition of said engine.
14. In refrigeration apparatus, in combination, means forming a space whose temperature is to be regulated, a refrigeration unit for said space, an internal combustion engine

25

adapted to drive an element of said refrigeration unit, starting means for said engine including a valve controlling the flow of air through the intake manifold of said engine, means responsive to the temperature of said space for controlling the operation of said starting means, and means responsive to pressure in said engine for regulating said starting means.

15. In refrigeration apparatus, in combination, means forming a space whose temperature is to be regulated, a refrigeration unit for said space, an internal combustion engine adapted to drive an element of said refrigeration unit, the operation of said unit being dependent upon the operation of said engine, starting means including a motor for turning over said engine and a valve for controlling the flow of air through the intake manifold of said engine, means responsive to the temperature of said space for controlling the operation of said motor, and means responsive to pressure in said engine for controlling said valve.
